BOTTOM-HINGED DOUBLE-HUNG WINDOW

Jean Vinant, Montreal, Quebec, Canada, and
Charles Alfred Racine, St. Petersburg, Fla.

Application March 5, 1951, Serial No. 213,922

4 Claims. (Cl. 20—45)

1

The present invention relates to a window construction and more particularly to a bottom-hinged double-hung window.

The general object of the present invention is the provision of a double-hung window of improved and simple construction, which is easy and simple to assemble and install and which is relatively economical to manufacture.

Another important object of the present invention is the provision of a bottom-hinged double-hung window having a maximum amount of light per opening.

Still another important object of the present invention is the provision of a bottom-hinged double-hung window in which the range of alternative ventilation possibilities is considerably increased over conventional double-hung windows.

Yet another important object of the present invention is the provision of a double-hung window of improved design in which cleaning is greatly facilitated inasmuch as the necessity of washing the windows from the outside is eliminated.

Another very important object of the present invention is the provision of a double-hung window in which the sashes may be completely removed without in any way disturbing the normal functions of the frames.

Yet another important object of the present invention is the provision of a bottom-hinged double-hung window made of extruded metal sections of standardized design and so shaped as to incorporate locking, hinging and holding means on the frame and on the sashes.

Still another important object according to the invention, is the provision of a double-hung window in which puttying of the glass panes is completely eliminated and in which said glass panes are readily inserted into suitable rail members but cannot be removed therefrom when the sashes are in vertical position.

Still another important object of the present invention is the provision of a double-hung window embodying weather stripping facilities and friction guides for the sashes.

Yet another important object of the present invention is the provision of a double-hung window having means whereby the upper sash may readily be displaced by operating the lower sash.

Yet another important object of the present invention is the provision of a bottom-hung double-hinged window in which the sashes may be swung inwardly and adjustably locked at any desired angle.

Yet another important object of the present invention is the provision of a double-hung window in which the sashes are easily removed and taken apart.

2

The foregoing and other important objects of the present invention will become more apparent during the following disclosure and by referring to the drawings in which:

5 Figure 1 is a perspective view of the window according to the invention showing the sashes in locked inclined position;

Figure 2 is a sectional elevation along line 2—2 of Figure 1;

10 Figure 3 is a perspective view of the window according to the invention showing the sashes and the glass pane guide members completely removed;

Figure 4 is a perspective view of the window showing the sashes in closed position;

Figure 5 is a fractional longitudinal section of the window in closed position;

Figure 6 is a fractional longitudinal section of the window showing how the sashes are swung inwardly together with the glass pane guide members;

Figure 7 is a fractional plan section along the line 7—7 of Figure 5;

Figure 8 is a fractional plan section along line 8—8 of Figure 5;

Figure 9 is a fractional perspective view of the lower rail member of the outer upper sash according to the invention;

20 Figures 10, 11 and 12 are fractional cross-sections of the lower sash rails of the upper and lower sashes of the window according to the invention showing how the lower sash is operated to displace the upper sash up or down;

Figures 13 to 17 are diagrammatic cross-sections of the window according to the invention showing some of the various possible positions of the sashes;

Figures 18 and 19 are diagrammatic cross-sections of a double double-hung window according to the invention; and

25 Figure 20 is a plan section along line 20—20 of Figure 18.

Referring now more particularly to the drawings in which like reference characters indicate like elements throughout the frame for the window, according to the invention, may be made of wood, metal or other suitable material adapted to fit masonry, brick or other openings as required. The lintel 1 is preferably provided with a longitudinal groove 2 for receiving the top rail of the top sash when it is in closed position.

Similarly the sill 3 is rabbed at 4 to receive the lower rail of the lower sash when the latter is in closed position.

30 The window frame is provided all around its outer edge with an abutment 5 projecting inwardly into the window opening and against which is set two side plates 6 which are perma-

nently secured to the jambs 1 of the window frame by means of screws 8 or the like.

The side plates 6, having L-shaped section as shown in Figures 7 and 8, extend the whole height of the window opening and are preferably made in extruded metal sections which may be cut to the desired length. They are provided with a longitudinal dovetailed groove 9 for interlocking with the corresponding dovetail projections 10 of the upper glass pane guide member 11 as shown in Figure 7, said latter member 11 being further secured to the side plate 6 by means of the screws 8.

The upper guide members 11 extend downwardly from the top or head of the window frame to about middle height and their lower edge 12 is bevelled as shown in Figure 5 or 6.

The upper guide members 11 are flat members provided with inward projections 13 and 14 spaced from each other and from the longitudinal edge of the guide member 11 so as to define channels for slidably receiving the glass panes 15 and 16. The side edge portions of the glass pane 15 of the lower inner sash is slidably inserted between projections 13 and 14 while the glass pane 16 of the upper outer sash slides between the projection 13 and the inwardly projecting leg 17 of the L-shaped permanently affixed side plates 6. The projections 13, 14 and leg 17 have preferably dovetailed grooves for receiving the weather strips 18 to ensure airtight joints between the glass panes and the metal frame sections.

The upper guide members 11 are further provided with a beaded portion 19 forming a circular groove the purpose of which will be described hereafter.

The lower glass pane guide members 20 have exactly the same cross-section as the upper glass pane guide members 11 except that the dovetail projection 10 is eliminated thereby permitting free lateral displacement of said lower guide members 20 relatively to the fixed side plates 6. They are bevelled at their upper end 21 to register with the lower bevelled end 12 of the fixed upper guide members 11 and they are pivoted at their lower end for inward swinging movement on the hinge plate 22 which is fixed to the sill 3 by means of screws 23.

The hinge proper comprises an L-shaped rod 24 having one leg freely extending within the sleeve 25 of the hinge plate 22 and the other leg freely inserted into the beaded portion 19 of the lower guide members 20. Thus the latter may be easily and rapidly removed from their hinge connections to the sill 3 as shown in Figure 3.

The lower end portion 25' of the guide members 20 is milled as shown in Figure 5 to allow movement over the hinge plate 22.

The guide members 20 may be swung inwardly and adjustably secured at any desired angle. Arms 26 are pivotally secured at their lower end by a pin 27 to a bracket 28 secured to the jamb 7 of the window frame by means of screws 29. The upper end of said arms is pivotally secured by a pin 30 to an extension 31 depending from a guide rod 32 slidably inserted into the beaded portion 19 of the lower guide member 20. A locking device, consisting in a disc 33 eccentrically mounted on the pin 30 and having a knurled periphery 34 to press against the outer face of the beaded portion 19 when rotated by means of the finger grip 35, serves to lock the guide rod 32 relatively to the guide member 20.

The lower guide members 20 are locked in closed position to the upper guide members 11 by means of a locking bolt 36 freely slideable in the beaded portion 19 of the guide members 11 and 20 and provided with a manipulating arm 37 which may be inserted into a slot 38 of the beaded portion 19 of the upper guide member 11 when the bolt 36 is in locking position or which may be inserted in a bracket or keeper 39 affixed to the top sash member 40 of the lower sash as shown in Figure 5. The arm 37 is placed in the latter position when the bolt 36 is in unlocking position its free upper end being below the upper edge 21 of the lower guide members 20 as shown in Figure 6.

The lower inner sash comprises the glass pane 15 and the top and bottom horizontally extending sash members 40 and 41 respectively, while the upper outer sash comprises the glass pane 16 and the horizontally extending top and bottom sash members 42 and 43 respectively. These sash members are cut at a suitable length to extend between the inner rabbeted shoulders 14' and 17' of the projections 14 and legs 17 of the guide members 11 and 20 and of the side plates 6 respectively.

These sash members have preferably a U-shaped cross-section, the inner face of their legs being serrated for gripping the edge portions of the glass panes 15 and 16 which are covered with suitable glazing strips so as to allow endwise entry of said glass panes between said legs but to prevent their removal.

The sash members may be removed from the glass panes by a sideways movement which may be effected only when the window is dismounted as shown in Figure 3 and after the glass pane guide members 20 have been removed.

The top sash member 42 of the outer sash is preferably provided with a circular groove 44 for the insertion of a suitable weather strip not shown. The lower sash member 43 is provided with a similar circular groove 45 into which may be inserted suitable blocking means, not shown, to secure the top sash in adjusted vertical position. The groove 45 also receives a hook 46, the purpose of which will be described hereafter.

The inner side face of the sash member 43 is provided with a dovetailed groove for the insertion of a weather strip 47, which is adapted to contact the top sash member 40 of the inner sash when the window is in closed position.

The sash member 40 is provided with an outer projection 48 at its end, adapted to overlap the sash member 43 to further insulate the window, according to the invention, when the sashes are in closed position.

A latching member 49 serves to lock the two sashes in closed position. It is inserted in the sash member 40 as shown in Figures 5 and 6, and is pivoted in a horizontal plane on a screw 50 to have its outer end 51 project within a registering groove 52 made in the sash member 43.

The lower sash member 41 of the inner sash is provided with a bottom circular groove 53 for the insertion of suitable means, not shown, to adjustably secure the bottom sash for different degrees of opening. The lower sash member 41 is further provided at its lower edge with an outwardly projecting curved extension 54, and also with a manipulating extension 55 projecting inwardly from the top edge thereof.

The sash member 41 is further provided with an inclined face 56 adapted to ensure a leakproof

contact with the inclined face of the rabbet 4 of the sill 3 when the window is in closed position.

As shown in Figure 9, the hooks 46 are pivotally secured in groove 45 of the sash member 43. The edges of the grooves 45 are punched in as shown at 51, thereby providing stop means to limit the sideways displacement of the hooks 46. These hooks 46 serve to displace the outer sash by operating the inner sash as shown in Figures 10 to 12.

To lift both sashes, the hooks 46 are swung inwardly so as to rest upon the extension 54 of the member 41 as shown in Figure 10. Thus by manipulating the extension 55 of the latter the top sash member 44 may be driven into the recess 2 of the lintel 1. To lower the two sashes, the hooks 46 are swung outwardly as shown in Figure 11 so that they may engage the underportion of the extension 54 as shown in Figure 12. The two sashes may then be displaced downwardly by means of the manipulating extension 55 of the inner sash.

In order to prevent falling apart of the outer glass pane 16 when swung inwardly in its lower position between the glass pane guides 20, the latter are provided with suitable retaining means for the glass pane such as the L-shaped leaf spring 58 shown in Figure 8 secured to the outer edge of said guide members 20. It is obvious that under these conditions the weather strips 18 on the leg 17 will extend only at the top half portion of the window opening.

In Figure 13 the window is shown with the sashes in closed position; in Figure 14, the top sash is partially opened; in Figure 15, the bottom sash is partially opened; in Figure 16, the bottom sash is swung inwardly together with the glass panes guide members 20 while the top sash is in its uppermost position, and in Figure 17, both sashes are swung inwardly.

Figures 18 to 20 show a double double-hung window built according to the present invention. All the elements previously described are simply duplicated except that the outer or double window will have preferably a smaller width so as to clear the side plates 6 of the inner window when swung inwardly.

Instead of having a double double-hung window as shown in Figures 18 to 20, double glass panes with an air space left therebetween may be substituted to the single glass panes 15 and 16.

From the foregoing description, it is seen that the window, according to the invention, may be easily installed for any size of opening, all the various elements being of standardized construction and having simply to be cut to the right dimensions. This double-hung window may be swung inwardly and locked at any suitable angle for proper ventilation. Furthermore, the sashes and the side glass pane guides 20 may be completely removed from their hinges for cleaning, reglazing, etc.

While a preferred embodiment according to the invention has been illustrated and described it is understood that various modifications may be resorted to without departing from the spirit and scope of the appended claims.

What we claim is:

1. In a window construction, a window frame, vertical side plates secured to said window frame, made of extruded metal and having an L-shaped cross-section to provide a leg projecting inwardly within the window frame, vertically extending glass pane guide members made of extruded metal and in two sections, the upper section secured to the top portion of said side plate, the lower sec-

tion hinged at its lower end to said window frame and movable from a closed position registering with the upper section and contacting said side plate to an open position swung inwardly, said guide members consisting of a flat member adapted to contact the side plates with one longitudinal edge abutting against the inner face of said leg, and of inwardly extending projections depending from said flat member spaced between themselves and from said longitudinal edge so as to define vertically extending channels between themselves and with the inward leg of said side plates, and means to lock said lower section in closed position.

2. In a double hung window as claimed in claim 1 wherein said locking means include a slit bead formed on said guide member sections, a rod-like member slidable in said bead to take a position across the junction of said sections, and a handle depending from said rod-like member and passing through the slit of said bead.

3. In a double hung window as claimed in claim 2 including means to maintain said lower section in open position comprising a second rod-like member slidable in said bead, an arm pivoted to said second rod-like member and to the window frame, and means to lock said second lock-like member in said bead.

4. In a double hung window construction, a window frame, vertical side plates secured to said window frame and made of extruded metal, said side plates having a L-shaped cross-section to provide a leg projecting inwardly within said window frame, vertical glass pane guide members made of extruded metal and in two sections, the upper section secured to the top portion of said side plate and having a bevelled lower end, the lower section having an upper bevelled end to register with the lower end of said upper section, hinged at its lower end to the sill of said window frame and movable from a closed position registering with the upper section and contacting said side plate to an open position swung inwardly, said guide members consisting of a flat member adapted to contact the side plates with one longitudinal edge thereof abutting against the inner face of said inward leg and of two inwardly extending projections depending from said flat member, spaced between themselves and from said longitudinal edge so as to define vertically extending channels between themselves and with the inward leg of said side plates, an outer glass pane slidably extending between said leg and one of said inwardly extending projections of said sections, an inner lower glass pane slidably extending between said two inwardly extending projections of said sections, and sash members secured to the horizontal edges of said glass panes and extending between the projections of said sections and the inward leg of said side plates.
